K. F. UNGERER

ROLLING MACHINE

Filed June 11, 1925

FIG. 1.

FIG. 2.

Inventor:
Karl Fr. Ungerer
by *H. Schaefer*
Atty.

UNITED STATES PATENT OFFICE.

KARL FRIEDRICH UNGERER, OF PFORZHEIM, GERMANY.

ROLLING MACHINE.

Application filed June 11, 1925, Serial No. 36,440, and in Germany December 21, 1923.

My invention relates to a support for the rolls of rolling mills of the type in which the rolls are not carried by supporting rolls but by bearings intermediate the main bearings of the roll, and journals of reduced diameter. Such intermediate bearings extend only over part of the perimeter of their journals and the exposed portion of the journal is protected by a cap of resilient material, for instance felt, which is held in position by an arched holder, preferably a U-shaped steel band.

When very thin sheets are rolled, it may happen that the sheet is forced into the interstice at the journal which it is bridging so that longitudinal corrugations will form in the sheets at each intermediate bearing. This drawback is overcome according to my invention by providing on the journal full diameter collars resembling those of a thrust bearing, which support the sheet at the journals.

This protecting cap and its holder must not project from the surface of the roll as otherwise the holder would interfere with the free passage of the sheet metal and, moreover, it would be rapidly worn down and therefore the diameter of the journals is so determined that the holder is slightly set back from the surface of the roll.

Preferably the bearings are staggered in parallel and adjacent rolls as otherwise the material would not be worked along a continuous line where such bearings are arranged.

In the drawing affixed to this specification and forming part thereof a device embodying my invention is illustrated diagrammatically by way of example.

40 In the drawings—

Fig. 1 is an end elevation, and

Fig. 2 is an elevation of a bearing designed according to my invention.

Referring now to the drawings, 26 is a bearing block in which the journal 12' of

a roll 25 is carried by means of a semi-circular brass 15. Two collars 27, 28, are formed on the journal, their diameter being equal to the diameter of the roll 25. A holder 29 is placed over the journal and cut open 50 for the collars 27, 28, so that it is subdivided into three arches, and a felt cap is inserted between each of said arches and the journal as indicated at 30 for the central arch. The arches are integral with a strip 31 on both 55 sides of the bearing block, and this strip may be adjusted by means of a bar 32 and a set screw 34.

The collars 27 and 28 prevent any lagging of the plate between them. It will be understood that the number and width of the collars must be chosen in accordance with given conditions, viz, thickness of plate, length of journal, and pressure exerted.

Instead of connecting both ends of the 65 strips 21, 22 to a common set screw 24, each strip might be provided with a set screw of its own so that each strip may be adjusted separately. This modification is so simple that it will readily be understood by an expert without being illustrated.

I wish it to be understood that I do not desire to be limited to the exact details of construction shown and described, for obvious modifications will occur to a person 75 skilled in the art.

I claim:—

An intermediate support for the rolls of rolling mills, comprising a journal of reduced diameter in a roll, a bearing extending over part of the perimeter of said journal, collars formed on said journal of a diameter equal to that of said roll, caps of resilient material extending over said journal where it is exposed between said collars, 80 and means for holding said caps in position on said journal.

In testimony whereof I affix my signature.

KARL FR. UNGERER.
